UNITED STATES PATENT OFFICE.

GEORGE S. FOWLES, OF NEW CASTLE, MAINE.

IMPROVEMENT IN APPARATUS FOR SUPPORTING AND VENTILATING WOUNDED LIMBS.

Specification forming part of Letters Patent No. 40,164, dated October 6, 1863.

To all whom it may concern:

Be it known that I, GEORGE S. FOWLES, of New Castle, State of Maine, have invented certain new and valuable improvements in apparatus for supporting and cleansing fractured limbs and other wounds; and I hereby declare that the following is a true and exact description of the same, reference being had to the accompanying drawings, and to the letters of reference marked thereon.

Figure 1 represents a plan view of my apparatus. Fig. 2 represents a vertical section, and Fig. 3 a side elevation of the same.

The letter A in Fig. 2 represents the frame of my machine, which consists of the two bed-pieces B and D, the corner-posts E, and the ties C and F. The bed-pieces B and D are placed parallel and about thirty-six inches apart, and are made of scantling three inches square, more or less. The bed-piece D is twelve inches in length, but may be made a little longer if necessary. The bed-piece B is only about eight inches in length. At each end of the two bed-pieces B and D there is a corner-post, E, made of boards two inches, more or less, in thickness, and of the same width as the ends of the bed-pieces. The corner-posts E extend upward from two to three feet at one end of the frame A, and a little less at the other end, those fastened to the ends of D being the highest. The corner-posts E are fastened to the ends of bed-pieces B and D by a screw.

C represents the ties, of which there are two, one on each side of the frame. The ties C extend at each end a little beyond the corner-posts E, and are set into F about half their thickness, their upper edge being flush with the top of E. The ties C may be made an inch thick and two inches in width.

The corner-posts E are bound together by two additional ties. (Marked F.) The ties F rest at each end on the bed-pieces B and D, and are cut in sufficiently deep to receive the corner-posts E, thus making their outer edge flush with the corner posts E. The ties F may be made two inches in thickness and four inches in width.

G represents a sheet of tin or zinc, slightly concave lengthwise, and forming the bottom of the frame A. The sides of sheet G rest on the top of ties F, which are made slightly con-

cave to receive G. The ends of G rest on the bed-pieces B and D.

H represents a rest intended to support the well leg of the patient, and is made of a board of suitable strength, but not so wide as the bed-piece D. The rest H is made about twenty inches in length, convex on its upper surface, and flat on the lower side. The rest H is placed in a line with the bottom of bed-piece D, and is fastened to D by means of a plate of spring-steel, two screws securing the plate to H and two to the bottom of bed-piece D, and space being left between the ends of rest H and bed piece D to allow H to play freely up and down.

K represents the adjustable shaft, which is attached by a single screw-bolt to the corner-post E opposite to the rest H. The shaft K, which may be considered an extension of tie F, is about twenty inches in length.

L represents a piece of india-rubber cloth, sufficiently wide to extend from the outer end of shaft K to a point four or five inches on the surface of plate G. The cloth L has a slit in it at its edge to admit the corner-post E, so that as much of the cloth L will lap on the rest H as on the end of plate G. The part of cloth L that laps on G is fastened to the ties F, and the parts that lap on rest H and shaft K may be secured in their position by small tacks or strong thread.

The letter m in Fig. 1 represents the strips of linen or cotton cloth designed to support the wounded limb, the number and size of these strips may be varied to suit the requirements of the surgeon. The strips m are fastened at their ends to metal points (marked e) on the outside of ties C, and can be easily adjusted to suit the comfort of the patient.

n represents a small metal rod, bent at each end so as to form the two legs marked d. The legs d must be sufficiently long to raise the horizontal rod n out of the way of the surgeon. The legs d are at right angles with rod n, and must be far enough apart to enter the staples in corner-posts E at opposite ends and lengthwise of the frame A.

P represents the water and ice reservoir, which is made of zinc or tin, being about a foot in length, a little less in width, and four or five inches in depth at the compartment designed to contain ice. The water-compartment

ment is deeper, having a hopper-shaped extension underneath it. (See Fig. 4.) The compartments are separated by a partition of zinc or tin, two or three inches in height. The reservoir P has two metal eyes attached at each end and near the top, through which the two rods marked o are made to pass. The rods o are hooked at their ends, so as to embrace the rods n, upon which they play lengthwise of the frame A, the rods o moving at right angles with the rods n. As the water-reservoir P can play upon the rods o which support it, it can be moved to any point over the concave plate G, so as to bring the water immediately over the wounded limb. At the bottom of the hopper-shaped extension of the water-compartment several small perforations are made, and into them are inserted wooden pins tapering to a point. The pressure of the water causes it to distill drop by drop on the wounded limb. Tepid water is first put into the water-compartment, and ice, being placed in the other compartment gradually melts and escapes above the top of the partition, thus by degrees reducing the temperature of the tepid water as the patient may be able to bear the change.

In operating my apparatus it is first placed on a bed and the patient's leg extended the length of the concave plate G in the easiest position in reference to his wound. The linen strips being passed under the limb, it is raised sufficiently high to admit of a free ventilation under it, at the same time the patient's body, which rests on the cloth L, is to be propped up with pillows at such an angle as will make

his posture easy. The well leg reposes on the rest H, and the patient is then in condition for the offices of the surgeon. The rest H and the shaft K can be shifted to opposite sides, so as to be adapted to the treatment of wounds in either leg.

The advantages resulting from the use of this apparatus are obvious. The wounded limb can be approached from either side and dressed without inflicting pain by changing its position. All purulent matter discharged from the limb falls upon the concave channel made to receive it, and is carried off to a vessel at the foot of the bed. Should there be any suppuration from the body of the patient, it is conducted either to the concave G or into a crease in the rubber cloth in the direction of the rest H, where it can be received into another vessel. The ventilation of the wounded limb and the removal of all offensive matter from the person of the patient place him in the most favorable circumstance for rapid recovery.

Having thus described my invention, what I claim, and desire to secure by Letters Patent, is—

1. The rubber cloth L, arranged in the manner and for the purpose herein specified.
2. The water and ice reservoir P, in combination with the rods n, the rods o, the legs d, and the concave G, the whole constructed and arranged as herein set forth.

GEORGE S. FOWLES.
